CENTERLESS GRINDING MACHINE

Original Filed May 5, 1926 2 Sheets-Sheet 2

UNITED STATES PATENT OFFICE

FRED M. KERN, OF DETROIT, MICHIGAN, ASSIGNOR, BY MESNE ASSIGNMENTS, TO CINCINNATI GRINDERS INCORPORATED, OF CINCINNATI, OHIO, A CORPORATION OF OHIO

CENTERLESS GRINDING MACHINE

Application filed May 5, 1926, Serial No. 106,959. Renewed January 9, 1929.

This invention relates to grinding machines and more particularly to machines wherein work of round section is respectively ground and rotated by a rapidly rotated grinding wheel and a slowly rotated work regulating wheel.

One of the objects of this invention is to provide a grinding machine of the above-mentioned character that will be of thoroughly practical and rugged construction and that will be capable of dependable operation and efficient action in practical use. Another object is to provide a grinding machine having opposed grinding and regulating wheels in which one of the wheels is mounted and controlled with respect to the other in a manner will adapted to meet certain conditions met with in practice. Another object is to provide a pivoted mounting for one of the wheels in a grinding machine of the above mentioned character that will be of inexpensive construction, capable of rapid and efficient control, and capable of achieving many thoroughly practical advantages. Another object is to provide a wheel mounting of the above-mentioned character that will be yielding and in which effective and reliable control of the yielding character of the mounting may be achieved. More particularly, another object of this invention is to provide a mounting of the above-mentioned character for the regulating wheel and to provide, also, for ease and reliability of control of the relation of the regulating wheel to the grinding wheel. Another object is to provide a mounting for the regulating wheel in a grinder of the above-mentioned character that will permit such a universal movement or control of the regulating wheel that certain peculiar classes of work may be rapidly and efficiently ground.

As conducive to a clearer understanding of certain of the more specific features of my invention, it may at this point be noted that it is often desirable to clean up or put a finish upon thin hollow bodies of substantially cylindrical shape, or solid or hollow bodies which are slightly out of round or slightly tapered but which are intended to be substantially cylindrical. It is not particularly

feasible, and often is impracticable, to attempt to clean up such bodies by grinding in the ordinary grinding machine because, if the body is irregular in shape by being slightly out of round or slightly tapered, too much stock might be removed from one end or from one side on account of the tendency of the machine to grind the body to a cylindrical form. In such an operation, if the body to be cleaned up were of a thin walled construction, one side of the wall might be ground too thin, or even ground completely through in certain spots. This, obviously, would be objectionable in bodies which were to be used for purposes requiring considerable strength or which were to be subjected to considerable pressure. It has been customary, heretofore, to clean up such bodies by hand so that they might be preserved by lacquering or the like.

It is, therefore, another object of the present invention to provide a grinding machine adapted to clean up a non-symmetrical piece of work without taking an excessive depth of cut at any point upon the work piece, and particularly a work piece of substantially cylindrical shape which is slightly out of round or slightly smaller at one end than at the other.

Another object is to provide a grinding machine having a grinding wheel and a regulating wheel that will be well adapted to meet certain varying conditions of hard practical use. Other objects will be in part obvious or in part pointed out hereinafter.

The invention accordingly consists in the features of construction, combinations of elements, and arrangements of parts as will be exemplified in the structure to be hereinafter described and the scope of the application of which will be indicated in the following claims.

In the accompanying drawings, in which is shown one of various possible embodiments of my invention,

Fig. 1 is an isometric view of a machine embodying the invention;

Fig. 2 is a plan view of the mounting for one of the wheels; and

Fig. 3 is an elevational view taken along the line 3—3 of Fig. 2.

Similar reference characters refer to similar parts throughout the several views of the drawings.

5 Referring now to the drawings and more particularly to Figure 1, there is shown a main frame or base 10 suitably formed at its upper left hand portion, as viewed in Figure 1, to rotatably support the spindle 11 upon which is mounted a grinding wheel 12. The spindle 11 is provided with a pulley 14 by means of which, through a belt 13, for example, the spindle 11 and the grinding wheel 12 may be driven from any suitable source of power to give the grinding wheel 12 a speed suitable for grinding.

In order that the work and grinding wheel may be moved relatively so that the grinding wheel may come in contact with all points on the surface of the work and thereby clean the work satisfactorily, I provide an arrangement for moving one of the wheels toward and away from the other so as to press against the work and bring the work into grinding contact with the grinding wheel in such a manner that a substantially uniform depth of cut may be taken upon all points of the surface of the work. A satisfactory arrangement for this purpose is indicated in the machine illustrated in the drawings wherein the work regulating wheel 15 is secured upon a spindle 16 mounted for rotation in suitable bearings (not shown) each contained within a bearing casing 17 mounted on a frame 18 (Fig. 3). One end of the frame 18 is secured to a shaft 19 held for rotary movement within a bearing 20 integral with a plate 21, so that frame 18 may swing about the axis of shaft 19 and the other end is acted upon by means including a weight 22 (Fig. 1) adjustably mounted near one end of a lever arm 23 secured upon a shaft 24 which is mounted for rotation in the frame of the machine. A link 25 is pivotally secured at one end to the lever arm 23 and at the other end to a lug 26 integral with the frame 18. The action of the weight 22 is to tend to swing the frame 18, and hence the regulating wheel 15, in a direction, about the pivot shaft 19, toward the grinding wheel 12. The plate 21 is mounted upon a slide 30 to turn about a pivot shaft 31 (see Figure 2), and is provided with rollers 32 (Figure 3) adapted to travel in a passage 33 between the slide 30 and the L-shaped stop plate 34 secured to the slide 30 by means of screws 35. The slide 30 may be moved along appropriate slideways mounted on the frame of the machine by turning a hand wheel 37 secured upon a screw shaft 38 passing through a nut 39 in the frame.

The work W may be maintained between the wheels for operating thereon in any suitable manner. In the machine illustrated, I

preferably provide for this purpose a roll 40 (Figure 3) mounted upon a shaft 41 for rotation in a pair of lugs 42 on a bracket 43, which rests upon the plate 21 and the slide 30 and is secured to the latter by means of bolts 44. The regulating wheel 15 is brought in contact with the work W, to push the latter into rotative contact with the grinding wheel, by means of spring pressed plungers 45 each adapted to move in a sleeve-like portion 46 in the frame 18 and rest upon a support 47 on the plate 21. One end of each plunger 45 is reduced in diameter to pass through a bearing plug 49 which is threaded into one end of sleeve 46 and which is provided with a hexagonal projection 50 so that the plug may be turned for the purpose of adjusting the compression of a spring 51 surrounding each reduced portion of the plungers 45 and engaging the bottom of the plug 49. The spring 51 tends to press the plungers downwardly and out of the sleeves 46 and to swing the work regulating wheel 15 (about the axis of shaft 19) towards the grinding wheel. The extent of this movement is limited by the provision of stop nuts 56 adjustably mounted upon the upper threaded end 57 on the plungers 45.

In accordance with certain features of my invention the movable wheel may be moved at a suitable speed, preferably by the operator, away from the other wheel so as to permit removal of the ground work and the insertion of new work. As illustrated, I provide a suitable mechanism for so moving the regulating wheel. This mechanism may include a foot lever 60 (Fig. 1) pivotally secured upon a shaft 61 mounted in the frame of the machine. A link 62 is secured at one end to the lever 60 and at the other end to a crank arm 63 keyed upon the shaft 24. As already above noted, the link 25 (Figs. 1 and 3) is pivotally connected, at 26, to the auxiliary frame 18 and at its other end is pivotally connected to one end of the lever arm 23 (Fig. 1) which is secured upon the shaft 24. Movement of the foot treadle 60, in response to foot pressure exerted thereon, swings the shaft 24 in clockwise direction, as viewed in Figure 1, thus pulling link 25 downwardly and thus swinging auxiliary frame 18 and the regulating wheel 15 (Fig. 3) in clockwise direction about the pivot 19. Movement of the frame 18 in the above-mentioned direction about its pivot 19 moves the regulating wheel 15 away from the grinding wheel 12. This movement of the regulating wheel 15 in a direction away from the grinding wheel 12 takes place in opposition to the action of the springs 51 and of the weight 22. In order to hold the work W upon the roll 40 when the wheels are separated, a blade 65 is mounted upon a bracket 66 integral with the plate 21. The blade 65, as will be clear from Figure 2, is preferably of sufficient extent lengthwise

of the grinding throat to dependably hold the work W on the work supporting roll 40 when the wheels are separated.

Suitable flexibility in the connections for supplying power to the movable wheel may be provided by an arrangement such as a slot 70 (Figs. 1 and 2) in one end of the spindle 16 for slidably mounting a pin 71 secured upon the shaft 72. The shaft 72 may be rotated from any suitable source of power, but in the machine illustrated it is connected with the spindle 11 by means of the belt 74, vertical shaft 75, and associated parts. Thus, the belt 74 passes over a pulley 15 (not shown) on the spindle 11 and under a pulley 76 on the shaft 77 of a pump 78 to a pulley (not shown) on a shaft 79 rotatably mounted in the frame 10 of the machine. Suitable gear mechanisms are provided within the casings 80 and 81 for transmitting power from the shaft 79 to the shafts 72 and 75. An idler pulley 82 is secured upon a shaft 83 in the casing of the pump 78 to press against the belt 74. An idler pulley 85 is mounted in a frame 86 pivotally mounted at the end of brackets 87 integral with the casing of the pump 78 and may be adjusted toward or away from the belt 74 by means of an adjusting screw 88 in the frame 86 adapted to engage a stop (not shown) on the arm 87. A suitable grinding liquid may be supplied from a pipe 89 and directed upon the work W as desired.

In operation, the grinding wheel 12 and the work regulating wheel 15 are rotated at rates suitable for respective grinding and rotating the work positioned therebetween by power supplied thereto through the belt 13 and associated parts. The regulating wheel 15 may be adjusted, by turning the hand wheel 37, to an appropriate position depending upon the size of the work W . The operator then pushes upon the lever or pedal 60 which causes the frame 18 to swing in clockwise direction, as seen in Figure 3, and hence to cause the wheel 15 to move away from the grinding wheel so that a work piece W may be placed between the roll 40 and the blade 65. The operator then releases the lever 60, and the wheel 15 automatically returns to its original position, by the action of weight 22 and springs 51, thus moving the work W away from the blade 65 and into rotative contact with the grinding wheel 12 and regulating wheel 15. The regulating wheel 15 will then press against the work, due to the action of the springs 51 and the weight 22, so as to bring all points in the surface of the work into contact with the grinding wheel in substantially the same manner, and thereby cause a depth of cut to be taken upon the work of substantially the same amount all over its surface. If the work W is larger at one end than at the other, the regulating wheel mounting will

turn about the pivot shaft 31 to bring the surface of the work entirely in contact with the grinding wheel 12. On the other hand, if the work is slightly out of round, the regulating wheel will move towards or away from the grinding wheel by turning about the pivot shaft 19 as required by the character of the work. In this manner the work piece may be cleaned up satisfactorily without danger of taking too much stock off its surface so that it may be used safely for purposes requiring considerable strength or resistance to internal or external pressure.

It may further be noted that the work supporting member 40, being mounted upon the carriage or plate member 21 partakes of the same movements, about the vertical axis of the pivot shaft 31, as does the regulating wheel 15, so that effective supporting of the work W and dependable maintenance of rotating contact of the work W with the regulating wheel 15, during the grinding operation on the work W by the grinding wheel 12, are achieved. It will also be seen that the springs 51 dependably act to urge the regulating wheel 15 in a direction toward the grinding wheel 12 and that the range of action of the springs 51 may be dependably controlled or limited, as by the stop nuts 56 (Fig. 3). The weight 22 (Fig. 1) is, as above pointed out, adjustably mounted on the lever arm 23 and may be adjustably positioned to vary the action of the springs 51 to any desired extent, it being noted that the nearer toward the shaft 24 (Fig. 1) that the weight 22 is moved along the lever 23, the less does it contribute toward the yielding action of the springs 51.

When the grinding operation is completed, the operator steps upon the foot treadle 60, thus moving the regulating wheel 15, against the action of springs 51, in a direction away from the grinding wheel 12, whence the work piece W may be removed and replaced by a new work piece. Movement of the regulating wheel 15 in a direction away from the grinding wheel 12, due to the relation of the work supporting roll 40 to the two wheels, causes the work W to move in a direction away from the grinding wheel, preventing marring of the finished work piece by the grinding wheel. The blade 65 acts, as above noted, to hold the work piece W on the work supporting roll 40 when the wheels are separated.

It will thus be seen that there has been provided in this invention a grinding apparatus in which the several objects hereinabove noted, as well as many thoroughly practical advantages, are successfully achieved.

As many possible embodiments may be made of the above invention and as many changes might be made in the embodiment above set forth, it is to be understood that all matter hereinbefore set forth or shown

in the accompanying drawings is to be interpreted as illustrative and not in a limiting sense.

Having thus described my invention, what I claim as new and desire to secure by Letters Patent is:

1. A grinding machine comprising a grinding wheel, means for rotating the grinding wheel rapidly to grind the work, and means to support a piece of work rotatively in contact with the wheel which permits free relative movement between the grinding wheel and work angularly and laterally of their axes whereby work having an uneven or non-symmetrical surface may be ground.

2. A grinding machine comprising a rapidly rotated grinding wheel and a slowly rotated work regulating wheel, means for maintaining a non-symmetrical work piece between the wheels, and means for mounting one of the wheels so as to move freely towards and from the other wheel as well as angularly, as required by the shape of the work to be ground to press the work into rotative contact with the grinding wheel.

3. A grinding machine comprising a rapidly rotated grinding wheel and a slowly rotated work regulating wheel, means for maintaining a work piece between the wheels, and a movable mounting for one of the wheels adapted to move about a pair of distant angularly disposed pivot points so as to permit movement of the wheel toward and away from the other wheel and hold the work in rotative contact with the grinding wheel.

4. A grinding machine comprising a rapidly rotated grinding wheel and a slowly rotated work regulating wheel, means for maintaining a work piece between the wheels, and a freely movable mounting for the work regulating wheel constructed and arranged to turn as required by the shape of the work about a pair of axes, one substantially parallel and the other substantially perpendicular to the work axis so that the regulating wheel may assume a position such as to press against and bring all points on the surface of the work in rotative contact with the grinding wheel.

5. A grinding machine comprising a grinding wheel and a work regulating wheel, one of which is pivotally mounted to move toward and away from the other, means for rotating the grinding wheel rapidly and the work regulating wheel slowly to respectively grind and rotate the work, means for maintaining a work piece between the wheels, and a manually controlled device for moving the mounting for said movable wheel to withdraw it and permit the removal and insertion of work between the wheels.

6. A grinding machine comprising a grinding wheel and a work regulating wheel, one of which is pivotally mounted to move

toward and away from the other, means for rotating the wheel rapidly and the work regulating wheel slowly to respectively grind and rotate the work, means for maintaining a work piece between the wheels, a manually controlled device for moving the mounting for said movable wheel to withdraw it and permit the removal of ground work, and means for automatically returning said wheel to its initial position.

7. In grinding apparatus, in combination, a grinding wheel adapted to be rotated at a relatively high speed, a regulating wheel adapted to be rotated at a relatively low speed, means for holding work of substantially round section in operative relation to said two wheels, and means for rotatably supporting one of said wheels, said last-mentioned means including a pair of carriages, one of which is mounted for free oscillation about an axis and the other of which is mounted for free oscillation about an axis and upon the other carriage and is provided with bearing means for rotatably supporting said wheel, one of said axes being substantially parallel to the axis of the work and the other axis being substantially at right angles to the axis of the work.

8. In grinding apparatus, in combination, a grinding wheel adapted to be rotated at a relatively high speed, a regulating wheel adapted to be rotated at a relatively low speed, means for holding work of substantially round section in operative relation to said two wheels, and means for rotatably supporting one of said wheels, said last-mentioned means including a pair of carriages, one of which is mounted for free oscillation about an axis and the other of which is mounted for free oscillation about an axis and upon the other carriage and is provided with bearing means for rotatably supporting said wheel, one of said axes being substantially parallel to the axis of the work and the other axis being substantially at right angles to the axis of the work, and spring means acting upon one of said carriages.

9. In grinding apparatus, in combination, a grinding wheel adapted to be rotated at a relatively high speed, a regulating wheel adapted to be rotated at a relatively low speed, means for holding work of substantially round section in operative relation to said two wheels, an auxiliary frame member having bearing means for rotatably supporting said regulating wheel, said auxiliary frame member being pivotally mounted upon an axis so to permit said regulating wheel to be moved toward or away from said grinding wheel when said auxiliary frame member is swung about its pivotal support, and mechanism for controlling the movement of said auxiliary frame member about its pivotal support.

10. In grinding apparatus, in combination,

- a grinding wheel adapted to be rotated at a relatively high speed, a regulating wheel adapted to be rotated at a relatively low speed, means for holding work of substantially round section in operative relation to said two wheels, an auxiliary frame member having bearing means for rotatably supporting said regulating wheel, said auxiliary frame member being pivotally mounted upon an axis so as to permit said regulating wheel to be moved toward or away from said grinding wheel when said auxiliary frame member is swung about its pivotal support, spring means urging said auxiliary frame and regulating wheel supported thereby toward the grinding wheel, thereby to cause the regulating wheel to urge the work toward the grinding wheel, and means for opposing the action of said spring means and adapted to permit said regulating wheel to be moved away from the grinding wheel, thereby to permit removal and insertion of work between said wheels. 5 70 75
11. In grinding apparatus, in combination, a grinding wheel adapted to be rotated at a relatively high speed, a regulating wheel adapted to be rotated at a relatively low speed, means for holding work of substantially round section in operative relation to said two wheels, an auxiliary carriage mounted to swing about an axis substantially at right angles to the axis of the work, a frame member pivotally supported upon said auxiliary frame and rotatably supporting one of said wheels, said frame member being adapted to oscillate about an axis substantially parallel to the axis of the work and thereby to permit movement of the wheel carried thereby toward or away from the other wheel, and means urging said auxiliary frame member in a direction to urge the wheel carried thereby toward the other wheel. 25 80 85 90 95 100 105
12. In grinding apparatus, in combination, a grinding wheel adapted to be rotated at a relatively high speed, a regulating wheel adapted to be rotated at a relatively low speed, means for holding work of substantially round section in operative relation to said two wheels, means mounting one of said wheels to permit it to be moved toward or away from the other, means mounting one of said wheels to permit its active work-engaging face to be positioned in substantial parallelism with the axis of the work and to be thrown out of parallelism therewith, and means operative upon said mounting means to urge one of said wheels toward the other and to cause the active portion of the operative face of one of said wheels to aline itself with axially extending irregularities in the surface of the work, and means for separating said wheels to permit the insertion or removal of work, said work-holding means being constructed to retain work substantially in operative position even though said wheels are relatively separated. 45 110 115 120 125 130
13. In grinding apparatus, in combination, a grinding wheel adapted to be rotated at a relatively high speed, a regulating wheel adapted to be rotated at a relatively low speed, means for holding work of substantially round section in operative relation to said two wheels, a slide carried by said main frame and movable toward or away from the grinding wheel, an auxiliary frame member having bearing means for rotatably supporting said regulating wheel, means pivotally mounting said auxiliary frame member upon said slide to pivot about an axis substantially at right angles to the axis of the work, thereby to permit the operative surface of said regulating wheel to aline itself with axially extending irregularities in the surface of the work. 60 135

axis so as to permit said regulating wheel to be moved toward or away from said grinding wheel when said auxiliary frame member is moved about its axis, and mechanism including yielding means for controlling the movement of said auxiliary frame about said axis.

17. In grinding apparatus, in combination, a main frame, a grinding wheel adapted to be rotated at a relatively high speed, a regulating wheel adapted to be rotated at a relatively low speed, means for holding work of substantially round section in operative relation to said two wheels, a slide carried by said main frame and movable toward or away from the grinding wheel, an auxiliary frame member having bearing means for rotatably supporting said regulating wheel, means pivotally mounting said auxiliary frame member upon said slide to pivot about an axis so as to permit said regulating wheel to be moved toward or away from said grinding wheel when said auxiliary frame member is moved about its axis, means for predetermining the position of said slide relative to said grinding wheel, and means operating upon said auxiliary pivoted frame member to swing it about said axis for changing the distance between the grinding wheel and the regulating wheel to permit insertion or removal of a work piece relative to said wheels.

18. In apparatus of the character described, in combination, a grinding wheel rotatable at a grinding speed; a work rotating wheel rotated at a speed much slower than said grinding wheel; said wheels forming a grinding throat therebetween and being rotated in respective directions so that the work rotating wheel controls the rotation of a round work piece in said grinding throat; means for holding work of round section in operative relation to said wheels; and means for conditioning said grinding throat for insertion or removal of work, comprising means mounting one of said wheels for oscillation about a pivot in a direction toward or away from the other wheel, and means for shifting the position of the pivot about which said mounting means may oscillate.

19. In apparatus of the character described, in combination, a grinding wheel rotatable at a grinding speed; a work rotating wheel rotated at a speed much slower than said grinding wheel; said wheels being rotated in respective directions so that the work rotating wheel controls the rotation of work of round section during the grinding operation thereon by the grinding wheel; means for holding work of round section in operative relation to said wheels; means mounting one of said wheels for oscillation about a pivot in a direction toward or away from the other wheel; and means permitting change of the angularity between the axis about which said mounting means may os-

cillate and the operative face of the other of said wheels.

20. In grinding apparatus, in combination, a grinding wheel adapted to be rotated at a relatively high speed, a regulating wheel adapted to be rotated at a relatively low speed, means for holding work of substantially round section in operative relation to said two wheels, an auxiliary frame member having bearing means for rotatably supporting said regulating wheel, said auxiliary frame member being pivotally mounted upon an axis so as to permit said regulating wheel to be moved toward or away from said grinding wheel when said auxiliary frame member is swung about its pivotal support, yielding means for yieldingly urging said auxiliary frame member to swing in one direction about said axis, and means for causing said auxiliary frame member to swing in the other direction about said axis.

21. In grinding apparatus, in combination, a grinding wheel adapted to be rotated at a relatively high speed, a regulating wheel adapted to be rotated at a relatively low speed, means for holding work of substantially round section in operative relation to said two wheels, an auxiliary frame member having bearing means for rotatably supporting said regulating wheel, said auxiliary frame member being pivotally mounted upon an axis so as to permit said regulating wheel to be moved toward or away from said grinding wheel when said auxiliary frame member is swung about its pivotal support, yielding means for yieldingly urging said auxiliary frame member to swing in one direction about said axis, and means for limiting the range of action of said yielding means.

Signed at Detroit, Michigan, this 29th day of April, 1926.

FRED M. KERN.
